UNITED STATES PATENT OFFICE.

CONSTANT GENTIL, OF ST. LOUIS, MISSOURI.

BRAKE FOR RAILWAY-CARS.

SPECIFICATION forming part of Letters Patent No. 228,752, dated June 15, 1880.

Application filed March 10, 1880. (No model.)

To all whom it may concern:

Be it known that I, CONSTANT GENTIL, of St. Louis, Missouri, have invented certain new and useful Improvements in Rail-Brakes for Railroad-Cars, of which the following is a specification.

My invention relates to that class of railroad-car brakes which employ supplemental shoes or runners attached to the frame of the car in such manner that they may be lowered to come in direct contact with the permanent rails of the road-bed and receive the weight of the train, so that the wheels will be out of contact with the rails and the entire weight of the car resting upon the shoes will slide but a short distance, owing to the greatly-increased friction-surface, and almost immediately stop the train.

The object of the first part of my invention is to provide a simple, strong, and effectual mode of attaching the brake-shoes to the framing of cars of ordinary construction, and in suitable means for suspending and releasing the shoes, to allow them to be brought into operation either to stop the train in its forward movement or act automatically to arrest the retrograde movement of a car or train of cars should the engine lose control of them, either because of the steepness of the grade of the road-bed that is being climbed or because of the accidental breakage of the couplings between the separate cars of a train; and, furthermore, in simple means for readily raising again and restoring the brakes to their normal or inoperative position beneath the cars.

The object of the next part of my invention is to provide improved means and facilities, under the control of the engineer, whereby the brakes of all of the cars may be under his control by means of mechanism independent of the locomotive-engine, so that the operation or non-operation of either need not govern or in any way interfere with the other.

The object of the next part of my invention is to provide, in connection with the above-mentioned mechanism, a frangible coupling-link at suitable points along the chain that operates the brake-shoe connections, so that when undue strain comes upon it the links will give way or part, and so that the light

cars of a train need not be destroyed by others more heavily loaded and actuated by much greater *vis viva* or latent force.

The object of the next part of my invention is to provide, in connection with the above-mentioned mechanism, means for sounding an alarm to the engineer should one or any number of cars of the train become detached, and thus enable him to at once repair the damage, and not leave a car upon the track to collide with the next passing train.

The object of the next part of my invention is to shield the chains or cables that run beneath the cars for actuating the brakes and alarms, to prevent them from fouling or becoming entangled with other objects, and, furthermore, to enable the chains to be readily replaced should they become disconnected.

The object of the next part of my invention is to provide the brake-shoes with bearing-plates of flat sheet or corrugated metal plates, which may be replaced when worn, and which will offer greater resistance to the effects of friction than the material of the shoes.

The object of the next part of my invention is to provide, in connection with the above-mentioned mechanism, self-adjusting flexible metallic couplings for connecting the steam-pipes of the engine and boiler with the steam-pipes of the tender, so that a limited independent movement of the engine and tender may be allowed without breaking the joint and allowing the steam to escape.

In the accompanying drawings, Figure 1 is a side elevation of an engine-tender and a single car, showing my improvements attached, and representing the forward shoes of the hind wheels in their operative position and the rear shoes of the front wheels in their raised or inoperative position; Fig. 2, a central vertical section of the same; Fig. 3, a bottom-plan view of a car upon an enlarged scale, showing my improvements applied thereto; Fig. 4, a cross-section on line *x x* of Fig. 3; Fig. 5, a perspective view of the latch mechanism for holding the brake-shoes in or releasing them from their raised or inoperative position; Fig. 6, perspective views of plain sheet-metal and corrugated sheet-metal plates to be placed beneath the shoes; Fig. 7, a side view of the frangible links provided with a

spring-latch, shown in an open and also in a closed position; and Fig. 8, a detached view, in elevation, of the steam-pipe coupling.

The invention hereinafter claimed may be 5 readily applied to cars of nearly all of the present well-known forms of construction without material change.

The form herein shown represents a car-frame, A, having four longitudinal timbers, 10 A' A² A³ A⁴, extending from end to end of the car. The brake-shoes B B' are suspended by links b b, pivoted at their lower ends to the shoe and at their upper ends to bolts b², passing from the outer to the adjoining inner longitudinal frame-timbers, A' A² and A³ A⁴, which gives them a most secure connection 15 and allows them to swing freely. The brake-shoes are also suspended from the car by other links, b' b', pivoted to the shoe at one end and 20 to the frame or pedestal C of the axle-boxes at the other.

The brake-shoes B and B' are braced and held securely by a lateral bolt, B², so that 25 they may be at all times held in proper relative position, and also enable them to be operated at the same time by a single mechanism.

A bail, B³, is connected at its ends to the opposite ends of the bolt B², near its connection with the shoe, by collars upon said bolt, 30 so that the latter may partially turn therein and form a loose joint. The middle part of the bail passes through and is jointed to a pivoted bolt, D, at or about its middle portion. One end of the bolt D is pivoted at d 35 to lugs D', secured to the framing of the car, and the other end is rounded and extends over to and across the latch-bracket E, between jaws e e, to one of which is pivoted a notched latch, E'. This latch E' extends 40 across from one jaw to the other and engages at its free end in a notch in the spring-catch E².

The free end of the bolt D passes between the jaws e e of the bracket and rests upon the latch E' when said latch is supported by its 45 spring-catch E²; but when the latch-bolt and brake-shoes are in their raised position they will all drop to the position shown at the rear wheels of Figs. 1 and 2 by first drawing the spring-catch E².

In order to raise the said parts to their 50 inoperative position, as shown at the rear of the front wheels in said Figs. 1 and 2, a shaft, F, is journaled in bearings f f, secured to the under side of the car-frame, so that said shaft 55 will extend across the car in such manner that a crank-handle may be applied to the end of the shaft to turn it.

A cord or chain, f', is connected at one end 60 to the bolt D and at the other to the shaft F, so that when the shaft is turned the chain is wound around it and raises the brake-shoes and bolt D, and its free end will first strike the notch e' in the free end of the latch E (shown in Fig. 5) and raise the latch until it 65 engages with and is held by the spring-catch E², so that all parts of the brake are again

restored to their normal and inoperative position.

The spring-latches and brakes are all operated by chains or ropes G G', passing through 70 the loops e² of the spring-catches E², and run under the cars from one end of the train to the other, and are secured at the rear end of the train to cleats, hereinafter described, and attached at the front end to a shaft or drum, 75 H, arranged transversely beneath the tender. This shaft H is to be revolved by a crank-wheel, H', and connecting-rod H² of a steam or compressed-air cylinder, H³, which may receive its steam, if that be the motive power, 80 from the boiler of the locomotive, or, if air be used, from an air-compression chamber attached to the cylinder, and supplied with compressed air by well-known means.

The shaft or drum H and its driving-engine 85 should be under the immediate control of the engineer, so that the safety-brakes may be operated at a moment's warning by turning on the power to the driving-engine of shaft H, which, operating upon the chains G, actuates 90 the spring-catches E², which release the latch E and bolt D, so that the shoes B may drop by their own weight and fall directly beneath the wheels and upon the rail in such manner that the wheels will roll up on the shoes, and 95 thus change the rolling motion of the train to a sliding motion, thereby greatly increasing the friction and bringing the train to an easy but almost immediate stop.

The rear ends of the chains G are attached 100 to the rear end of the last car by hitching them over cleats g g, secured to the car-frame, preferably at each end, so that the chain may be secured at either or both ends of the car.

The chains G G' are connected between each 105 car by frangible hooks or links g' g', (see Fig. 7,) preferably made of soft malleable iron, open at one side, so that if undue strain comes upon it the link will give way and allow the chain to part. An advantage of this frangible link 110 is that when the chain has been wound up by the drum sufficiently to release all the brakes the chains will part at such points of connection only without material damage to the chain, as a new link can be immediately substituted for the old one in reconstructing the 115 train.

The links g' g' are preferably closed at the split side by a spring-latch, g², which will allow the chains to be readily connected but 120 prevent their accidental separation.

The chains G G' are held in place by sheaths 125 G², which consist of sheet-metal tubes open at the ends and suspended from the car-frame by brackets G³, so that said chains are prevented from lateral or other displacement when covered by said sheaths. These sheaths G² extend from each end nearly to the middle of the car, but so that an intervening space is left between them at a point opposite the latch 130 mechanism. The chains diverge toward the middle of the car at this point in order that

they may pass through the loop of the spring-catch, and so that when drawn taut by the shaft H it will partially straighten out and draw the spring-catch E laterally to release 5 the brakes.

The sheaths G² are slotted from end to end on their upper side, as shown in Fig. 4, to admit of a finger or hook to catch into the links of the chain and pass it entirely through the 10 sheath with but little trouble.

In the construction and arrangement of the parts herein shown two lines of chain, G G', are employed, arranged upon opposite sides of the car. The first line above described may be 15 connected with the latch mechanism of the brake-shoes, located in front of the rear wheels to check the forward movement of the cars, and the chains G', connected with the mechanism for operating the brakes, that prevent 20 the retrograde movement of a car or train in case of their being detached in climbing a grade. This is often the case in roads of heavy gradients, as the couplings are subject to great strain and sometimes sever their connection, 25 and cars are left behind and wreck the next train. In such cases the engineer should be at once apprised of such disconnection, in order that the detached car or cars be again coupled with the train. This object is effect- 30 ually accomplished by the following means: The chains G' are for this purpose connected at the forward end of the train to the end of an iron rod, I, passing longitudinally beneath the tender. This rod is surrounded 35 by a coiled spring, and is arranged to be drawn through its bearings in one direction by the chain and forced back into its original position by the spring. The foremost end of this rod I is provided with a pivoted 40 hanging or spring pawl, i, which projects downward therefrom and bears against the free end of the spring-arm of a hammer, K. This spring-arm passes through a downwardly-inclined slot, l, in a vertical plate, L, so that 45 when the hammer-arm has been drawn back to the end of its stroke by the pawl i it will be forced down the slot l until it is out of contact with the pawl, and the hammer is allowed to fly back to its first position and strike against 50 the alarm-gong M as the spring-pawl on its return movement passes over the end of the hammer-arm in position for a repetition of the operation. The hammer strikes in this case against the large gong M, suspended beneath the tender, and gives the alarm; but the same device 55 may be used to start a spring-alarm capable of striking a succession of rapid blows upon the gong.

The chains may be united and crossed at 60 the point of connection between the first car and tender, so that both sets of brakes may be operated (and the alarm sounded also) should there be reason for stopping the cars suddenly and locking the wheels from the front and 65 rear.

The brake-shoes may be provided with sole-

plates B⁴, made of sheet metal, preferably corrugated, and attached to the under or bearing surface of the shoes in a simple manner, in order that they may be readily removed and 70 replaced to prevent the destruction of the shoe-block by friction upon the rails.

The steam-pipe of the boiler is connected to the steam-pipe of the tender by a simple V-shaped coupling formed of jointed pipe-sections N N' N² N³. Three thimble-joints, n n' n², are formed by one overlapping the other, 75 screwed together and properly packed to prevent the escape of steam, as shown in Fig. 8. It will be readily seen that as the pipes N N³ 80 approach each other the angle formed by the pipes N' N² will simply become more acute without interfering with the function of the device.

The brake mechanism above described is 85 more especially adapted to freight-trains, as it is not expensive or liable to get out of order. As this mechanism is only to be used at times of imminent danger, the derangement of parts incident to its use is immaterial. By locating 90 the shoes, as shown, between the wheels of trucks of a car they are out of the way of the ordinary hand-brake, and as the soles of the shoes are provided with flanges they are not liable to leave the track. 95

The rear shoes will be found to be peculiarly serviceable on narrow-gage mountain roads of steep gradients, as trains are often required to be temporarily stopped upon an up grade when the steam is low and the engine overtaxed. Any one of the brakes may be lowered independently of the others by hand, 100 should it be required to simply lock a car temporarily upon a grade, by securing a short rope from the spring-latch E² to the side of the car. 105

A single car in a train fitted with these appliances will work to good effect in braking a train, and any one of these cars may be coupled with others not provided with this particular brake without interfering with the 110 making up of the train.

Having fully described my invention, what I claim, and desire to secure by Letters Patent, is—

1. The combination, with a railroad-car frame, of shoes suspended therefrom by links, so that when the shoes are down they will rest upon the track beneath the wheels, crank-shafts F, and chains to lift the shoes, and a latch mechanism secured to the car-frame centrally to hold the brake-shoes horizontally out of contact with the rails and wheels, substantially as and for the purpose described. 115

2. The combination, with a railroad-car frame, of the shoes B, lateral bolt B², bail B³, locking-bolt D, and latch E, substantially as 120 shown, and for the purpose described.

3. The combination, with a railroad-car frame, of shoes suspended therefrom and adapted to rest on the rails, bail B³, locking-bolt, latch, and spring-catch for supporting 125 the shoes above the track, and chains or cables 130

running the length of the car to operate upon the locking mechanism, substantially as and for the purposes set forth.

4. The combination, with an engine, car, or tender, of a steam-cylinder, a shaft or drum driven from said cylinder, chains running therefrom the length of the train, with the brakes constructed to be raised horizontally and so dropped on the track, and operating mechanism, as described, for applying said brakes simultaneously by power under the control of the engineer, substantially as described.

5. The combination, with a railroad engine or tender and a series of shoes adapted to fall under the wheels of a train, of an alarm-gong to be connected with chains that pass beneath the cars and control said shoes in such manner that should the couplings be broken at any point of the train the alarm will be sounded at the same time that strain is brought upon the chains and the shoes are dropped under the wheels, substantially as described, for the purpose specified.

6. The combination, with a railroad-car, of 25 brake-shoes adapted to fall under the wheels, chains for operating said brakes arranged beneath the car, and tubular sheaths permanently secured on each side of the center of the framing thereof to hold the chains in 30 proper position and protect them, substantially as described.

7. The tubular chain-sheaths secured to the car-frame on each side of the axial line thereof and slotted longitudinally, in combination 35 with shoe-sustaining latches and spring-catches secured to a car-frame out of line of said tubular sheaths, substantially as and for the purpose described.

8. The combination, with a chain or chains 40 operating upon shoe-sustaining spring-catches, of a rod, I, a pawl, i, pivoted to the latter, a hammer, K, a slotted guide-plate, and a gong, substantially as and for the purpose described.

CONSTANT GENTIL.
